UNITED STATES PATENT OFFICE.

FRANK W. BARTLETT, OF BERKELEY, CALIFORNIA, ASSIGNOR TO UNION MACHINE COMPANY, A CORPORATION OF CALIFORNIA.

BRIQUET-PRESS.

1,057,029.

Specification of Letters Patent.

Patented Mar. 25, 1913.

Application filed May 16, 1911. Serial No. 627,507.

To all whom it may concern:

Be it known that I, FRANK W. BARTLETT, a citizen of the United States, and a resident of the city of Berkeley, county of Alameda, 5 and the State of California, have invented a certain new and useful Improvement in a Briquet-Press, of which the following is a specification.

The invention relates to improvements in 10 a press or molding machine for forming and pressing briquets, blocks or other similar bodies.

The object of the invention is to provide 15 a press in which the time required for forming the briquet and removing it from the die is greatly lessened.

Another object of the invention is to provide 20 means for closing the lower end of the die which may be quickly removed from, or 25 placed in, position below the die to allow the pressing to be made or the finished briquet to be removed.

The machine is particularly adapted for 25 making briquets from pulverized or granular salt, although it may be used for pressing and molding other substances but in the description I will confine myself to the use of the press for making salt blocks.

In the manufacture of salt blocks there 30 are substantially three steps in the process; first, the charging of the die with the material to be pressed; second, the actual pressing operation and third, the removal of the 35 pressed block from the die. A certain specified time is required for the actual pressing operation and it is not the object of this invention to reduce this time in any marked degree. The time saved by the use of the present machine occurs in the first and third 40 operations; that is, in arranging the die in condition for receiving the charge and in charging, and in removing the finished briquet from the die. These two steps in the 45 operation have heretofore required the larger percentage of time and by greatly reducing the time of these operations, many more pressings per hour are obtainable.

This device possesses other advantageous 50 features, which, with the foregoing will be set forth at length in the following description, where I shall outline in full that form of embodiment of the invention which I have selected for illustration in the drawing accompanying and forming part of the 55 present specification.

The novelty of the invention will be included in the claims succeeding said description. From this it will be apparent that I do not limit myself to the showing made by such drawing and description as I may 60 adopt many variations within the scope of my invention as expressed in said claims.

The drawing is a vertical section of the press, showing the plunger in the raised position. 65

The press consists of a pressure cylinder 2 having a piston 3 thereon, to which is attached the plunger 4. Below the plunger 4, in a suitable frame 5 is the die 6 in which the plunger 4 operates to compress the material. 70 Located above the die 6 is a suitable feed hopper 7 from which the material is fed into the die. The plunger 4 acts as a gate for the hopper and allows the material to enter the die only when the plunger is raised. In the 75 present instance a rectangular plunger is used and the sides of the lower end of the hopper are formed to engage the plunger to prevent it from turning and thereby hold it in proper alinement with the die. A stop-piece 8 on the plunger prevents the lower end of the plunger from emerging from the lower end of the die.

Arranged below the die 6 is a short cylinder 9 provided with a piston 12. The cylinder 9 is spaced apart a sufficient distance from the lower end of the die to allow the briquet to be ejected from the die and to be removed laterally from between the die and the piston 12. 80 85 90

Arranged on the piston 12, and slidable laterally thereon, on the tracks or guides 13 is a locking block 14, which is of sufficient transverse area to cover the opening in the lower end of the die. The height of the locking block 14 is slightly less than the distance between the lower face of the die and the surface of piston 12, when said piston is in the depressed position. The locking block 95 is preferably made of a height substantially the same as the height of the compressed material, so that there will be sufficient room for extracting the briquet when the locking block is moved laterally to open the die, but it is evident that the locking block can be made of greater height without sacrificing any of the advantages of the invention. 100

The locking block 14 is moved into and out of position below the die by means of the piston 15 operating in the cylinder 16. 110

The piston rod 17, connecting the piston 15 with the locking block 14, is slidably mounted in the locking block to allow said block to have a slight vertical movement under the 5 action of piston 12.

Attached to the forward side of the locking block 14 is the apron or chute 18, which lies under the die when the locking block is drawn backward and which receives the 10 briquets as they are ejected from the die.

The die is preferably made slightly tapered toward the lower end, so that the briquet is moved downward to eject it from the die, it is freed from the die and readily 15 drops away from the die. This taper extends substantially for the full length of the compressed briquet, so that a slight movement of the plunger after the locking block has been withdrawn will loosen the 20 briquet. The taper is not shown on the drawings, on account of the slightness thereof and the small scale of the figure.

Suitable connections are made with the various cylinders for admitting fluid under 25 pressure thereto, and suitable valves may be employed for controlling the flow of the fluid.

Heretofore, as far as I am aware, the closing of the lower end of the die was accomplished by a piston located similar to piston 12, but having a longer stroke. Since sufficient distance must be left between the bottom of the die and the surface of the piston in its depressed position to allow the briquet to be removed there between, it is evident that the piston would have to move 35 through the great distance at each stroke. The pistons are generally operated by hydraulic pressure and the movements of the 40 piston are slow, so that considerable time was consumed in raising the piston and al-

lowing it to lower after the pressing operation.

With the press of my invention the piston 12 is moved only a sufficient distance to release the locking block or to raise the locking block into engagement with the die. When the locking block is in the raised position the valve controlling the water inlet to cylinder 9 is left open, so that the locking 45 block is firmly held against the die and is not displaced when pressure is applied to the material within the die. After the pressing operation the valve is closed and the piston allowed to recede. The locking 50 block is then withdrawn and the briquet is ejected from the die.

I claim:

1. In a press of the character described, a die, a hydraulically operated vertically movable member below said die, and a laterally movable locking block of substantially the same height as the compressed material arranged on said member and adapted to be moved to open and close the lower end of 60 the die.

2. In a press of the character described, a die open at both ends, a hydraulically operated plunger coating therewith, a vertically movable member below said die and spaced 70 apart therefrom, a laterally movable locking block arranged on said member adapted in one position to close the end of the die, said locking block being of substantially the same height as the compressed material, and 75 hydraulically operated means for moving the vertically movable member to move said locking block into contact with said die.

FRANK W. BARTLETT.
